UNITED STATES PATENT OFFICE.

ROBERT J. ELDREDGE, OF WAVERLY, IOWA.

SPANNER-LUG.

1,305,529.

Specification of Letters Patent. Patented June 3, 1919.

Application filed February 10, 1919. Serial No. 276,201.

To all whom it may concern:

Be it known that I, ROBERT J. ELDREDGE, a citizen of the United States, residing at Waverly, in the county of Bremer and State 5 of Iowa, have invented certain new and useful Improvements in Spanner-Lugs; and I do declare the following to be a full, clear, and exact description of the invention, such as will enable others skilled in the art to 10 which it appertains to make and use the same.

My invention relates to improvements in devices commonly known to the trade as spanner lugs, intended to anchor the ends 15 of silo or tank hoops, without the necessity of extending them across the doors or other openings. I am aware that devices for this purpose have heretofore been devised, but the object of my invention is to improve 20 upon their construction to such an extent as to render manufacture and installation less expensive and less arduous, and at the same time to provide a device which will be more efficient than those heretofore employed.

With the above end in view, the invention resides in the novel construction hereinafter 25 fully described and claimed, the descriptive matter being supplemented by the accompanying drawing which forms a part of this 30 application.

Figure 1 is a side elevation of the invention installed upon a silo.

Fig. 2 is a horizontal section on the plane 35 of the line 2—2 of Fig. 1.

Fig. 3 is a detail perspective view.

In the drawings above briefly described, the numeral 1 designates a rectangular frame consisting of upper and lower strap iron bars 2 and angle iron end bars 3 having 40 their ends riveted at 4 to the ends of the bars 2, so that one flange 5 of each end bar extends outwardly from the frame as shown. Metal channels 6 are spaced outwardly from and are parallel with the central portions of the end bars 3, and each channel is by preference formed of two lengths of angle iron 7, these lengths being so arranged that their flanges 8 and 9 form, respectively, the side flanges and the body 45 portions of the channels. Strap iron bars 10 are secured at one end by the rivets 4, between the bars 2 and 3, the bars 10 at each end of the frame being disposed in outwardly converging relation and having their outer ends given a quarter twist at 11 and inserted between the flanges 9 of the two

metal channels 6, rivets or other fasteners 12 being passed through said ends and flanges, as shown clearly in Figs. 1 and 3.

Between their ends, the body portions of 60 the metal channels 6, which portions are formed by the flanges 9, are provided with openings 13 to receive the ends 14 of a silo or tank hoop, the nuts 15 of said hoop ends engaging the innermost of said flanges 9 65 when the frame 1 is in place around a doorway or other opening 16 in the silo or tank. The innermost of the flanges 7 rest against the wall of the silo or tank as seen in Fig. 2 and thus space the nuts 15 outwardly 70 therefrom to such an extent as to permit easy tightening of said nuts by means of a wrench; and when this tightening takes place, the channels 6 will withstand the strain without warping as is the case when 75 merely one angle iron is provided for engagement with each nut 15. The latter arrangement exerts all pull upon one flange of the angle iron and thus twists or cant the latter so that its other flange injures the 80 silo or tank wall. By giving the bars 10 the quarter twist at 11, the use of metal channels instead of angle iron is permitted, and said bars may be attached to the body portions of said channels so that the central strain 85 exerted by the nuts will be centrally received by the bars and will thus have no tendency to bend or twist either these bars or the channels.

Preferably used in connection with the 90 features above described, are two angle iron strut bars 17 which are riveted at 18 to the bars 10, in close proximity to the end bars 3, one flange 19 of each bar 17 extending outwardly beside the adjacent flange 5. By 95 this arrangement, inward swinging of the bars 10, which would be allowed should bending of the end bars 3 take place, is prevented, since the two bars 3 and 17 at each end of the frame will positively resist the 100 strain and will serve to brace each other against longitudinal bowing.

By constructing the device in the manner shown and described, it may be easily and inexpensively constructed of ordinary strap 105 iron and angle iron and no forging or welding whatever is necessary. In addition to these manufacturing advantages, the device will be most efficient in use, particular emphasis being laid upon the fact that the 110 frame cannot vertically collapse, due to the twin bars 3 and 17; and upon the quarter

twist 11, together with the use of the channels 6.

Since probably the best results are obtained from the details disclosed, they may 5 well be followed, but within the scope of the invention as claimed, numerous minor changes may well be made and it is to be understood that the device may be used wherever applicable.

10 I claim:

1. A spanner lug comprising a rectangular frame, relatively short, metal channels spaced outwardly from and parallel with the central portions of the frame ends, the 15 side flanges of said channels extending away from said frame ends, and two pairs of strap metal bars secured respectively to the frame ends and converging toward said metal channels, said bars being given a quarter 20 twist and having their outer ends secured to the body portions of said channels, at the ends of the latter, said body portions of the channels having central openings to receive the threaded ends of a silo hoop or like 25 member.

2. A spanner lug comprising a rectangular frame, relatively short, metal channels spaced outwardly from and parallel with the central portions of the frame ends, each 30 of said metal channels being formed of two lengths of angle iron disposed side by side with the side flanges of said channels extending away from said frame ends, two pairs of strap metal bars secured respectively to said frame ends and converging 35 toward said channels, said converging bars being given a quarter twist and having their outer ends inserted between the angle iron flanges forming the body portions of said 40 channels, and fasteners passing through said bar ends and flanges to secure them together, said last named flanges having cen-

tral openings to receive the threaded ends of a silo hoop or like member.

3. A spanner lug comprising a rectangular frame having end bars of angle iron, outwardly converging bars secured to the corners of said frame, the outer ends of said bars having means for attaching thereto the ends of a silo hoop or like member, and angle iron strut bars secured at their ends to said converging bars and located in close proximity to said angle iron end bars, whereby the outwardly extending flanges of said end and strut bars may serve to brace 55 each other.

4. A spanner lug comprising a rectangular frame having angle iron end bars, metal channels spaced outwardly from and parallel with the central portions of said end bars, 60 each of said metal channels being formed of two lengths of angle iron disposed side by side with the side flanges of said channels extending away from said end bars, strap metal bars secured to the corners of said 65 frame and converging toward said channels, said converging bars being given a quarter twist and having their outer ends inserted between the angle iron flanges forming the body portions of said channels, fasteners 70 passing through said bar ends and flanges to secure them together, said last named flanges having central openings to receive the threaded ends of a silo hoop or like member, and angle iron strut bars secured at 75 their ends to said converging bars and located in close proximity to said angle iron end bars, whereby the outwardly extending flanges of said end and strut bars may serve 80 to brace each other.

In testimony whereof I have hereunto set my hand.

ROBERT J. ELDREDGE.
